UNITED STATES PATENT OFFICE

CARL RIEGER, OF AALEN, GERMANY

WASHING MANGLE

Application filed January 13, 1928, Serial No. 246,595, and in Germany January 20, 1927.

My invention relates to mangles or wringers adapted to be moved from their operating position above a table-top to a position underneath thereof so that the machine can be used both as a mangle or wringer as well as an ordinary table.

As distinguished from the usual collapsible mangles or wringers, according to the present invention the height of the table whether 10 the mangle occupies the operating position or has been moved under the table always remains the same and furthermore, the portions of the divided table top are so arranged that, when the mangle has been lowered to a 15 position under the table, they form a continuous surface. Also, because of the novel construction, the movement of the mangle to a position underneath the table can be easily effected by one person without any risk.

20 These advantages are attained in that the mangle or wringer is loosely carried by an axle located under the table-top, about which axle the mangle can be swung so as to be readily lowered to its inoperative position. 25 For this purpose, an open space is left underneath the table-top so that the mangle not only hangs free but can also swing free of any stays or other parts of the frame and avoid damage thereto, should it be inadvertently released while being lowered. Thus, 30 any pinching of the fingers or other injuries are safely prevented.

In order to make the mangle or wringer movable in the above manner, it is employed 35 without spring bends passing over the rollers, in which the mangle rollers are arranged in lateral springs. In this way, the mangle has not only a small weight, so that it can be moved into and out of operative position 40 with a slight effort but also the mounting of the operating crank at the side clear of the standard is facilitated.

The two halves of the table-top lying in 45 front of and behind the mangle or wringer, are slidably mounted on a transverse shaft extending from the front to the back of the machine and they are moved towards one another on this shaft, after the lowering of the mangle to its inoperative position. The 50 two table top halves do not then project sub-

stantially, and therefore not inconveniently, above the standard.

An embodiment of the invention is illustrated in the drawing in which

Figures 1 and 2 are lateral views of the 55 machine respectively showing the mangle in and out of operating positions.

Figures 3 and 4 are respectively a front view and a top plan view of the machine. The mangle comprises the rollers *a*, carried in approximately U-shaped springs *b*, which are arranged at both ends of the rollers *a*, so that the weight of the mangle is comparatively small. The mangle or wringer together with its frame *c* can be swung about a shaft *d*, provided at the front of the machine and extending under the table-top *e* transversely of the machine. The mangle or wringer can thus be swung about the shaft *d* to be suspended therefrom underneath the table top, 70 as shown by Fig. 2. The position of the suspended mangle is so chosen in relation to the centre of gravity of the machine that in its suspended position it does not project beyond the table-top *e* (see Figure 2).

Moreover, there are no portions, such as struts or the like, against which the mangle could strike by swinging.

In the operative position of the mangle claws *f* on the frame *c* rest on a shaft *g* longitudinally extending underneath the table-top *e*.

To enable the mangle to be swung easily, a handle *h* is provided on the rear side, which, by the person standing before the mangle, is gripped above the rollers *a*. The operating crank is made detachable so that it does not hinder the swinging of the mangle.

The swinging of the mangle is possible 90 after the table-top *e* has been raised to an upright position as shown by the broken lines in Fig. 3. To this end, the halves of the table are mounted on an axle *k* as shown in Figure 3. The axle *k* is horizontally disposed on one 95 of the outer sides of the table-top *e* extending from the front to the back. The table-top halves *e* are movable with their collars *m* on the axle *k* so that they can be moved together into contact with one another, after the man- 100

gle has been lowered to the position shown in Fig. 2.

I claim:

In combination, a table comprising spaced frame members, a rod carried by one of said frame members, a pair of table top sections, at least one of which is mounted on said rod for swinging movement to and from a horizontal position and also for sliding movement towards and from the other section, 5 mangle supporting brackets each pivotally supported at one end beneath said other table top section for swinging movement between a substantially horizontal position to dispose 10 a mangle carried by said brackets above the table top and a substantially vertical position in which the mangle is suspended beneath the table top, and means carried upon the lower side of the slidable table top section for 15 co-operation with the free ends of said brackets to support the latter in their horizontal positions.

In testimony whereof I affix my signature.

CARL RIEGER.
